UNITED STATES PATENT OFFICE.

FREDERIK MARINUS VAN GELDEREN, OF ENSCHEDE, NETHERLANDS.

INSULATING CAP FOR THE JOINTS OF ELECTRICAL CONDUCTORS.

Application filed October 18, 1927. Serial No. 226,974.

This invention relates to insulating caps for the joints of electrical conductors, and more particularly to caps for insulating the bare ends of said conductors.

5 In my prior Patent No. 1,460,624, I have shown an insulating cap of this type, said cap having an internally threaded cavity in which is located a conical coil of spring wire. When the cap with the spring therein 10 is screwed on the bare ends of the conductors, the spring gradually expands in radial direction due to the introduction of the conductors, and this radial expansion brings more or less of the intermediate portion 15 of the spring into contact with the grooves of the threads of the insulating cap, the extent of the contact being determined by the size of the conductors upon which the cap and coil are threaded. Thus the conductors are firmly bound together and secured within the cap, in effective electrical connection with one another.

In the use of a cap of this type, unless care is exercised by the electrician to cut 25 the ends of the wires exactly the right length, or if the total diameter of the twisted wires is not sufficiently great, it frequently happens that the extreme ends of the conductors protrude beyond the innermost turn 30 of the coil when the latter has reached the limit of its inward movement and strike the bottom of the cavity of the cap before the conductors are properly bound and tightly secured in the cap. As a result, further rotation of the cap on the conductors produces 35 no tightening effect and it becomes impossible under such conditions to obtain a firm connection and reliable insulation.

It is an object of the present invention 40 to avoid the aforesaid difficulty, and I have found that this object may be accomplished by the provision of a well or supplemental cavity at the bottom of the principal bore, or inner bore in case the cap is provided with 45 inner and outer bores; a stop being provided for limiting the inward movement of the coil.

Another object of the invention is to 50 provide a coil of such form that it will more effectively engage both the thread of the cap and the surface of the united conductors than results from the use of the coil shown in my prior patent mentioned. This is accomplished by employing for the coil metal

wire which in cross section is square or 55 rhombic.

The invention will be more readily understood upon reference to the accompanying drawing, wherein:

Fig. 1 represents a longitudinal section 60 through an insulating cap provided with a well at the bottom of its cavity in accordance with the present invention, the cap being considerably enlarged;

Fig. 2 is a similar view of a cap of somewhat different form internally and showing the wire coil in place within the cap before the application of the latter to the conductor,

Fig. 3 is a view similar to Fig. 2 but showing the coil expanded by the conductor to 70 which the cap has been applied, and

Fig. 4 is a longitudinal section through another form of cap.

In the drawing the numeral 1 represents an insulating cap of porcelain or other suitable insulating material. The cap is hollow as shown and is provided with an internal thread 2. As shown in Fig. 1, the thread 2 extends almost to the open end of the cap, where it opens into the shallow recess 3. 80 In the form illustrated in Figs. 2 and 3, the outer threaded bore 3^a is of substantial depth and its inner end merges into the inner bore about midway the entire depth of the cavity. The cap shown in Fig. 4 is 85 of the same general form as that shown in Figs. 2 and 3, but the outer conical bore 3^b is not provided with screw threads.

The wire coil is indicated in Figs. 2 and 3 by the numeral 4, and as illustrated is of 90 polygonal cross section. Conveniently the section may be square, but it may be rhombic or other form which will provide an outer angle on the coil for engagement with the thread of the cap and an inner angular 95 portion for gripping the surface of the united conductors to be connected and insulated.

As shown in Fig. 2, only the larger convolution at the inner end of the coil 4 100 engages the threads 2 when the coil is threaded into the cap. The coil has the general form of a double cone, and the portion of smallest diameter is preferably close to the inner end of the coil. The inner diameter at the smallest section must, of course, be somewhat smaller than the external diameter 105 of the thinnest conductor joint which

is to be insulated with a particular cap. At its wider, or end portions, the inner diameter of the coil must be slightly larger than the thickest conductor joint with which the cap 5 is to be used.

The supplemental cavity or well 5 is preferably of smaller diameter than the bottom of the cavity of the cap and extends below the inner end of the thread 2, which end 10 forms a stop 5' for limiting the inward movement of the wire coil by abutment therewith of the inner end of the coil. Other modes of effecting engagement of the coil with the thread of the cap and for limiting the inward movement of the coil when the cap is applied to the conductor may be employed, but that illustrated is quite practical and inexpensive.

In the use of the device described, the cap 20 is applied to the bare ends of the conductors to be united and rotated thereon. The wire coil engages the conductors and firmly unites the same. As the inward movement of the conductors progresses, the intermediate portion 25 of the conical coil 4 becomes expanded and may ultimately engage the thread within the cap to a greater or less extent. In the absence of the well, should the complete binding effect and the tightening of the cap 30 on the conductors not be effected before the ends of the latter strike the bottom of the bore, further rotation of the cap on the conductors is useless and an efficient joint and insulation cannot be secured. By the provision 35 of the supplemental bore, however, the protruding extremities of the conductors are free to move inward the necessary distance to permit the coil to proceed in its movement until interrupted by engagement 40 of its inner end with the stop 5' and to expand as completely as it will into the groove in the cap; in other words, until the maximum binding effect is produced.

As shown in Figs. 2 and 3, the outer bore 45 3^a is threaded for engagement with the insulation 6 on the separate conductors to provide a firm and substantially water-proof connection.

It will be understood that the cap is useful for insulating the joints of electrical conductors even if the wires happen to be cut so short that the well is not necessary, and it will be obvious, therefore, that with the use of the device described it is not necessary 55 for the electrician to be particularly careful as to the length of wire bared before applying the cap, so that considerable time can be saved.

What I claim is:

60 1. An insulating cap of the type including a body of insulating material having a cavity therein, and a metallic insert in said

cavity, said insert having an internally threaded tapered passage therethrough for receiving and binding the bare ends of electrical conductors when the cap is applied thereto and rotated, characterized by the fact that said body of insulating material is provided with a well below said cavity for receiving the ends of conductors which protrude beyond said cavity and the metallic insert therein. 65 70 75 80

2. The combination with an insulating cap for the bare ends of electrical conductors, said cap having a cavity therein provided with an internal thread, of a tapered coil of wire for receiving and binding the bare ends of the conductors when the cap is applied thereto and rotated and having a free end below the turn of smallest 85 diameter extending laterally to engage and move along said thread, and a stop comprising the inner end of said thread for limiting the inward movement of said coil, said cap having a well below said stop for receiving the ends of conductors which protrude beyond said cavity. 90

3. The combination with an insulating cap for the bare ends of electrical conductors, said cap having a tapered cavity therein provided with an internal thread, of a conical coil of wire for receiving and binding the bare ends of the conductors when the cap is applied thereto and rotated, and having a free end below the turn of smallest 95 diameter extending laterally to engage and move along said thread, and a stop comprising the inner end of said thread for limiting the inward movement of said free end, said cap having a cylindrical well below 100 said stop and of smaller diameter than the lower end of the cavity for receiving the ends of conductors which protrude beyond said cavity. 100

4. The combination with a hollow insulating cap for the bare ends of electrical conductors, said cap being internally screw-threaded, of a metal coil for receiving and binding the bare ends of the conductors when the cap is applied thereto and rotated 110 and having means for engaging the thread, the said coil being formed of wire of non-circular cross-section which presents a sharp thread-forming edge at the interior of the coil. 115

5. An insulating cap as set forth in claim 4, wherein the wire forming said coil is of polygonal cross-section and arranged to present thread-forming edges at the interior and at the exterior of the coil. 120

In testimony whereof, I affix my signature.

FREDERIK M. VAN GELDEREN.
